UNITED STATES PATENT OFFICE.

JAMES A. MOULD, OF MILWAUKEE, WISCONSIN, ASSIGNOR TO EVINRUDE MOTOR COMPANY, OF MILWAUKEE, WISCONSIN, A CORPORATION OF WISCONSIN.

OUTBOARD MOTOR.

Original application filed March 5, 1923, Serial No. 622,740. Divided and this application filed November 8, 1924. Serial No. 748,610.

To all whom it may concern:

Be it known that I, JAMES A. MOULD, a citizen of the United States, residing at Milwaukee, county of Milwaukee, and State 5 of Wisconsin, have invented new and useful Improvements in Outboard Motors, of which the following is a specification.

This invention relates to improvements in outboard motors, and more particularly to 10 steering and reversing mechanism therefor. This application is a division of my application Serial No. 622,740, filed March 5, 1923.

In common with the invention disclosed 15 in the application above referred to, it is the general object of this invention to provide positive means for locking the tiller handle in connection with the drive shaft housing during ordinary operation of the 20 device, while permitting the drive shaft housing to be freed from the tiller for separate rotation for reversing purposes. Heretofore the torque of the driving connections 25 to the propeller has been relied upon to keep the drive shaft housing in abutting relation with some part connected with the tiller. When the engine is at rest in such 30 a device the torque referred to is no longer in existence, and as a consequence, steering becomes impossible. It is the purpose 35 of the present invention to maintain a positive connection between the tiller and the dirigible parts of the outboard motor irrespective of whether the engine is in operation or not.

The more particular object of the invention claimed in this divisional application is the provision of a device in which a very simple positively acting releasable mechanism is employed for the purposes aforesaid, the connections between the tiller and such mechanism being direct and as simple as possible. It is a further object of this invention to provide for the transmission of 45 movement between the tiller grip and the locking mechanism for the dirigible parts, while permitting the tiller grip to oscillate in a vertical plane for the purpose of preventing injury to the operator upon occasions when the motor tilts.

In the drawings:

Figure 1 is an elevation of an outboard motor embodying this invention.

Figure 2 is a section taken on line 2—2 55 and illustrating the internal construction

of the tiller and latch mechanism forming the particular subject matter of this application.

Like parts are identified by the same reference characters throughout the several 60 views.

The outboard motor which is shown complete in Figure 2 may be of the general type disclosed in the patent to Evinrude, No. 1,001,260, August 22, 1911. The device includes a crank case 10, cylinders 11, and fly wheels 12. The fly wheel is mounted upon a crank shaft 9 which leads downwardly, as disclosed in said patent, through a dirigible shaft housing 13 to a submersible 70 gear housing 14, wherein suitable gearing connects the crank shaft with a propeller shaft upon which the propeller 15 is mounted. Constructional details which are fully shown in the Evinrude patent named above, 75 and which are unnecessary to an understanding of the present invention, have been omitted from the drawings herein in order to simplify the disclosure.

The bracket 16 is adapted to support the 80 entire motor including the internal combustion engine, driving connections, and propulsion mechanism from the stern or transom of a row boat or other small craft. The bracket is provided with spaced arms 85 17 and 18, the latter of which is elongated to extend downwardly outside of the transom to a point adjacent the water line. A set screw 19 in the shorter arm 17 of the bracket may be turned up to engage the 90 transom of a boat with a clamping pressure.

Immediately beneath crank case 10 is a casing 22 which houses latch mechanism forming an important part of this invention and hereinafter to be described in detail. 95 The casing 22 is preferably secured by bolts to the crank case 10, or is otherwise made fast thereto. A two-part bearing sleeve 24 supports for oscillation the latch casing 22. A pintle 31 connects bracket 16 with one 100 part of sleeve 24, thereby providing a hinged joint permitting the motor to tilt.

The peripheral flange 33 of the bearing sleeve is in supporting relation to the latch casing 22. Thus, the bearing between 105 shoulder 34 and the peripheral flange 33 of the two-part bearing sleeve 24 carries the entire weight of the engine and propulsion mechanism. Upon this bearing the engine and propulsion mechanism may be 110

oscillated as a unit upon the axis of crank shaft 9 for steering purposes. The dirigible tubular housing 13 for the downwardly extended crank shaft 9 is rigidly connected with the submersible gear housing 14 in which the propeller shaft is journaled. Thus, when the engine and related parts are oscillated in bearing sleeve 24, the direction of the thrust of propeller 15 is angularly adjusted and effects the steering of the craft to which the motor is attached. Steering is further facilitated by the webs or fins 35 which are preferably integral with the submersible gear housing 14 and comprise a rudder dirigible with said housing.

The latch mechanism releasably connecting the tiller with the dirigible tubular housing 13, and the attached submersible gear housing 14 and rudder 35 will now be described.

The dirigible tubular housing 13 extends upwardly through the sleeve 23 which forms an integral part of the latch casing 22. The annulus 36 disposed within the latch casing 22 is secured to shaft housing 13. This annulus carries upon its periphery a pair of symmetrically disposed radially projecting lugs 29 with which means is engageable to effect the latching operation.

Formed integrally with latch housing 22 is the bearing sleeve 40 which, in the normal centered position of the latch housing, is disposed at one side thereof and projects forwardly thereof, as is clearly shown in Figure 2. Rotatable in bearing 40 is a shaft 41, upon the end of which is supported a worm 42 preferably having square threads 43 as indicated. These threads preferably project into very close proximity to the annulus 36 so that the lugs 29 carried by such annulus cannot be rotated by the annulus past the worm 42 without meshing with and passing between the threads.

The bearing member 40 terminates in a pair of spaced ears 44 and 45 from which the aligned pivot pins 46 projecting inwardly to carry the sleeve extension 47 for pivotal movement about the horizontal axis represented by said pins. The sleeve extension 47 rotatably supports the tiller proper designated by reference character 48 and provided at 49 with the usual hand grip. The tiller proper comprises a rod or shaft which is rotatable in sleeve extension 47 and is movable therewith in a vertical plane for oscillation about pins 46. The sleeve 47, however, is secured by said ears against rotation, whereas the tiller 48 may be rotated and is in universal connection at 49 with shaft 41.

A suitable set screw 50 may be threaded into casing member 22 for engagement with the end of shaft 41 to force the screw 42 axially into engagement with the end of bear-

ing member 40, thereby to limit the possible end play of such shaft and to hold the universal joint in a centered relation to the horizontal axis represented by pivot pins 46.

It will be noted particularly that the tiller, in its normal position, is in axial alignment with the worm or screw 43 which comprises the latch. Rotation of the latch, therefore, is accomplished without the use of intermediate connections such as those employed in the parent application above referred to of which this is a division. The direct connection between the tiller and the latch results in great economy of manufacture and in a simplified construction.

In operation, one of the lugs 29 will normally be engaged by worm 43 in the manner indicated in Figure 2. The threads 43 contacting said lug upon opposite sides thereof will obviously serve as a positive lock for engaging the tiller-oscillatory casing member 22 with the shaft housing 13, whereby to transmit to the shaft housing and related parts all movements of the tiller irrespective of whether or not the engine is operative.

When it is desired to reverse the direction of operation of the outboard motor the tiller handle is rotated whereby to transmit rotative movement directly to the rotary latch or worm 43. By such rotative movement the lug 29 which is engaged by the worm is fed through the worm between threads 43 and is ultimately delivered from engagement by said threads. Immediately upon its delivery in this manner the torque developed by the engine and the drive to the propeller will cause the shaft housing 13 and annulus 36 and other parts connected therewith to rotate approximately 180° until the other of lugs 29 contacts with the threads 43 of the worm and brings the shaft housing and related parts to rest. If the lug strikes an inclined portion of threads 43 the impact may be sufficient to cause the worm to rotate slightly to receive and positively to lock the lugs. Otherwise it may be necessary for the operator, upon feeling the impact, to rotate the worm slightly until the lug has been fed into the threads of the worm to a position corresponding to the position of lug 29, as indicated in Figure 2. In such a position the propeller will be in the full line position in which it is shown in Figure 1, and the motor will propel rearwardly a craft to which it is connected.

When it is desired again to reverse the motor to resume forward propulsion of the craft, the tiller is turned in the same direction as formerly to feed lug 29 through worm 43 and again to release the parts for rotation caused by the torque of the driving connection.

The pivotal movement of bearing member 47 and the universal joint connecting shaft

sections 41 and 48 is useful only where the motor is of the tiltable variety, in which oscillation occurs about a transverse horizontal axis to permit the submerged parts of the 5 motor to swing upwardly when a submerged obstacle is encountered thereby. When the motor tilts as aforesaid, a rigid tiller handle will be oscillated into contact with the rear seat of the boat to which the motor is attached and serious injury to the hand of the 10 operator might result. In the construction herein illustrated the motor is free to tilt with respect to the tiller, due to the universal joint in the tiller and to the horizontal 15 pivot by which the bearing 47 is mounted. This arrangement transmits to the steering parts of the motor all movements of the tiller in a horizontal plane while leaving the tiller free to swing about the axis of pins 20 46 in a vertical plane. Thus, when the motor tilts the hand of the operator will not be forced against the seat and nevertheless a positive connection will be maintained through the universal joint between the 25 grip portion 49 of the tiller and the worm or latch member.

I claim:

1. In a device of the character described, the combination with an outboard motor 20 having rotatably mounted dirigible parts, of a manually operable shaft adapted for connection with said parts for steering purposes, and latch mechanism directly connected with said shaft and operative releasably 35 to engage said shaft positively with one of said parts.

2. The combination in an outboard motor having rotatably mounted dirigible parts, 40 of latch mechanism mounted for oscillation co-axially with said parts, a manually operable shaft directly connected with said latch mechanism, and complementary latch mechanism connected with one of said parts and adapted for positive interconnection 45 with said oscillatory latch mechanism, said first mentioned latch mechanism being formed for releasable positive engagement with said complementary latch mechanism upon the rotation of said shaft.

50 3. The combination in an outboard motor having rotatably mounted dirigible parts, of a controlling device for said parts supported for oscillation co-axially therewith and including a latch casing, latch mechanism 55 supported for non-restricted rotation in said casing about an axis substantially normal to the axis of rotation of said parts, and adapted upon rotation to engage said parts positively and during its continued rotation 60 in the same direction subsequently to release said parts, and a manually operable shaft directly connected with said latch mechanism and projecting therefrom substantially upon the axis of movement thereof, whereby to be adapted to actuate

said mechanism for the release of said parts without requiring intermediate motion transmitting connections.

4. In a device of the character described, the combination with the rotatably mounted 70 dirigible parts of an outboard motor, of a head carried by said parts and provided with lugs projecting radially, a casing mounted for oscillation co-axially with said parts, a shaft journaled in said casing for rotative movement about its own axis, said shaft being disposed substantially tangentially with reference to the path of movement of said lugs, and latch mechanism mounted on said shaft and movable therewith and adapted releasably to engage said lugs.

5. In a device of the character described, the combination with the rotatably mounted 85 dirigible parts of an outboard motor, of a head carried by said parts and provided with lugs projecting radially, a casing mounted for oscillation co-axially with said parts, a shaft journaled in said casing for rotative movement about its own axis, said shaft being disposed substantially tangentially with reference to the path of movement of said lugs, and latch mechanism 90 mounted on said shaft and movable therewith and releasably to engage said lugs, said mechanism including members adapted to engage each lug upon opposite sides thereof, whereby positively to lock said casing to said head.

6. In a device of the character described, the combination with rotatably mounted 100 dirigible parts of an outboard motor, of a head connected with said parts and provided with a radially projecting lug, a latch casing supported for oscillation co-axially with said head, and latch mechanism comprising a worm mounted in said casing for intermeshing engagement with said lug.

7. In a device of the character described, the combination with rotatably mounted 110 dirigible parts of an outboard motor, of a head connected with said parts and provided with a radially projecting lug, a latch casing supported for oscillation co-axially with said head, and latch mechanism comprising a worm mounted in said casing for intermeshing engagement with said lug, together with a manually engageable member operatively connected with said casing and 120 said worm for controlling the oscillation of said casing and the rotation of said worm.

8. In a device of the character described, the combination with rotatably mounted 125 dirigible parts of an outboard motor, of a head connected with said parts and provided with a radially projecting lug, a latch casing supported for oscillation co-axially with said head, and latch mechanism comprising a worm mounted in said casing for intermeshing engagement with said lug, to 130

- gether with manually engageable shaft means operatively connected with said casing and said worm for controlling the oscillation of said casing and the rotation of said 5 worm, said shaft means being in direct connection with said worm and including a portion projecting from said casing for manual engagement.
9. An outboard motor including the combination with a member rotatably adjustable for steering and reversing purposes and provided with a radially projecting lug, of a tiller rotatable upon its axis, and latch means rotatable with said tiller for positively 10 engaging said lug upon opposite sides, said means being operable by the rotation of said tiller to a lug releasing position.
10. In an outboard motor the combination with a member rotatably adjustable for 15 steering and reversing purposes and bodily adjustable upon a transverse axis, of bodily rotatable latch mechanism adapted to be releasably engaged with said member and connected for bodily movement therewith, a tiller 20 connected with said latch mechanism and having a grip portion independently adjustable vertically, and means operatively connecting said latch mechanism and said tiller for manually rotating said latch mechanism for the release of said member.
11. In an outboard motor the combination with a member rotatably adjustable for 25 steering and reversing purposes, of lugs carried by said member, a casing enclosing the portion of said member which carries 30 said lugs, a screw-threaded device rotatably mounted in said casing and adapted to act upon said lugs, a bearing sleeve integral with said casing and extending outwardly therefrom, said sleeve comprising two portions hinged upon a transverse horizontal axis, and a shaft connected with said screw-threaded device and extending through said 35 sleeve and provided with a universal joint aligned with the axis upon which said sleeve is hinged.
12. An outboard motor including the combination with a member rotatably adjustable for 40 steering and reversing purposes, of a radially projecting lug upon said member, a tiller rotatable upon its axis and universally jointed intermediate its ends, a bearing sleeve bodily movable about the axis upon which said member is adjustable and provided with journals upon each side of said 45 universal joint, said sleeve being hinged for movement upon one axis passing through said universal joint but not upon another, and a latch mechanism connected to said tiller and bodily movable with said tiller 50 sleeve and adjustable by the rotation of said tiller to and from a position for engagement with a lug upon said member.

JAMES A. MOULD.
